UNITED STATES PATENT OFFICE.

SAMUEL ERASTUS MOWER, OF NEW HAVEN, CONNECTICUT, ASSIGNOR TO HENRY GRANT THOMPSON, OF SAME PLACE, AND HENRY G. THOMPSON, OF MILFORD, CONNECTICUT.

MACHINE FOR INSERTING STAPLES.

SPECIFICATION forming part of Letters Patent No. 309,081, dated December 9, 1884.

Application filed May 12, 1884. (No model.)

To all whom it may concern:

Be it known that I, SAMUEL E. MOWER, of New Haven, county of New Haven, State of Connecticut, have invented an Improvement 5 in Machines for Inserting Staples in Boots and Shoes and other Articles, of which the following description, in connection with the accompanying drawings, is a specification, like letters on the drawings representing like parts.

10 In the manufacture of shoes, especially of that kind known as "buttoned" shoes, there is very considerable strain at the junction of the button-hole piece and the vamp. So, also, in laced shoes the strain is very considerable 15 at the junction of the quarters and vamp. These points, which are subjected to the greatest strain when pulling the foot into the shoe, are now commonly provided with stays, produced by making a number of stitches back 20 and forth, or by using a larger thread or cord, or by employing a rivet, as in the cheaper class of shoes known as "brogans."

My invention has for its object the production of an automatic machine for inserting a 25 staple into the uppers or vamps of boots and shoes, to constitute stays, the mechanism herein shown as embodying my invention being adapted to make its own staples.

Figure 1 is a side elevation, partly in section, of a machine embodying my invention; Fig. 2, a front elevation of the cam-disk which operates the driver and the feed-actuating mechanism, the said figure showing the link to be attached to the driver, the studs for lifting the driver and presser-bars being shown in section; Fig. 2^a, a sectional detail below the line x^x, Fig. 1. Fig. 3 is a front elevation of the machine shown in Fig. 1; Fig. 4, a detail, to be described. Figs. 5 and 6 are details representing the front of the machine, the face-plate and the pivoted former being removed, the presser and driver being in different positions. Fig. 7 is a longitudinal vertical section of most of the parts of Fig. 5, 45 part of the former over which the wire is bent into staple shape being added. Fig. 8 is a detail to illustrate the presser and its action, and Fig. 9 is a detail showing part of the left side of the presser to illustrate the fixed but adjustable member of the wire-cutter.

The main frame A of the machine, supported, as herein shown, upon a column, B, contains the main shaft a, which is provided with

suitable clutch parts, a' a², under the control of a lever, a³, and a rod, a⁴, extended to a 55 suitable treadle, whereby the said shaft may be rotated once and then stopped, as is commonly done in boot and shoe nailing machines. The main shaft a at one end is provided with a disk, C, secured thereto by a suitable key 60 or feather, and provided at its rear side with a cam-hub, c', and at its front face the said disk is provided with a cam, 8, made as a groove. The cam-groove 8 receives a roller-stud, f', connected, as shown in Fig. 1, with 65 the presser-bar f, which is fitted to slide in suitable guideways made in the head A², removably attached by suitable screws to the flange A³ of the frame part A. This presser is recessed longitudinally at its front side, and at 70 its lower end has applied to it a plate, n', (see Figs. 5 and 6,) so as to leave behind the said plate a space or throat, 54, through which to drive the staple into the work. Above this plate n' the said presser has secured to it two 75 side plates, n², which are applied to the presser f by screws 53, so as to project just below the curved or beveled lower ends, 52, of the side walls of the presser, (see Fig. 8,) the same being cut through to form a space, 20, for the reception of the wire 34, as will be described, the said ends 52 constituting staple-bending surfaces to co-operate with the former m in the formation of the staples, as shown in Fig. 8, wherein it will be understood that the central part of the 80 staple s is held in the notch at the lower end of the former and that the presser is descending, the figure showing the presser as having been depressed sufficiently far to permit the end of the short piece of wire to be drawn out of the 85 groove 20, thus completing the staples, ready for the descent of the driver i', as will be described. The upper end of the plate n' is notched (see Figs. 5, 6, 7) for the reception of part of the lower end of the former m, (see 90 Fig. 7,) pivoted at 22 on the face-plate g of the head A², the said former being notched transversely at its lower end at m², (seen best in Fig. 7,) and provided at its upper end with a toe, 23. (See Fig. 1.) The presser at its lower 95 end is slotted vertically for the reception of a spring-latch, 10, attached thereto by a screw, 24, and the said latch has an inclined face above its shoulder. The disk C has a pin, 26, on which is placed a link, h, provided at its 100 upper end with a pin, h', which is extended 105

through the driver bar or carrier *i*, (see Fig. 1,) fitted into a groove, 44, in the head, (see Fig. 5,) the driver *i*' being placed in a groove, *m*², in the driver bar or carrier, and over a pin, 28, in the said bar or carrier, so as to be reciprocated in unison with it. The driver *i*' is shown as a flat but stiff steel bar, which passes behind the edges of plates *n*² into the space 54 behind the plate *n*' in the lower end of the driver, and is, preferably, concaved or countersunk to fit the crown of the staples to be driven, the said link and pins and disk actuating the driver positively as the shaft *a* is rotated. The presser *f* slides between guide plates or ways *g* *g*, attached to the head of the machine by screws 29. The upper end of the driver-carrier is made cam-shaped, or is provided with a beveled steel plate, as shown at 25, Fig. 1, to act against the toe 23 of the former *m*. The wire-guiding block 9, attached to the head of the machine by the screw 30, extended through a slot, 31, therein, so as to provide for adjustment of the said block, has its groove placed opposite one of the notches 32 in the notched disk or plate 33, of steel, placed in a recess in the left side of the presser, and arranged therein and held by a screw, 56, next the inner end of the grooved block 9, the inner corner or end of the said block and the said disk or plate forming the cutter members for severing the wire. The edges of one of the notches of the disk 33 becoming worn, the disk may be turned, thus bringing another notch into operative position. The legs of the staples to be formed and driven, as will be described, are clinched upon an anvil, 12, having two concavities. (See Figs. 1 and 5.) The anvil is held in an anvil-block, 13, by a screw, 45, and the shank 40 of the said block is extended down through, preferably, an india-rubber block, 46, and a hand-operated nut, 47, screwed into the socket 14 of the bed 15, one or more set-nuts, 48, being placed upon the lower end of the said shank. The rotation of the nut 47 in one or the other direction enables the anvil-block and anvil to be raised or lowered, and the india-rubber block, or it might be a spring, enables the anvil to have a limited amount of yield to the stock. Instead of said india-rubber block or spring, I may employ a metal collar. The wire is fed forward by a feeding device comprised, as herein shown, of an arm, *d*², having an attached block, *d*', a spring-held annulus, *d*³, and a wedge-block or annulus holder, *d*⁴. The annulus is placed over the hub *e*' of a washer, *e*², connected by screw 40 with the arm *d*², a pin, 41, preventing the hub from being rotated on the said pin. The inner diameter of the annulus is considerably larger than the external diameter of the said hub *e*', and a spring, 42, connected at one end to the said hub, and placed between the said hub and annulus, as shown in Fig. 4, tends to keep the annulus in such position that as the arm *a*' is moved in the direction of the arrow in Fig. 3 the annulus, by the action of the wire,

will first be moved back far enough to wedge itself under the inclined lower edge of the serrated block or holder *d*⁵, which latter will engage the serrated edge of the said annulus, thus causing it to bite the wire closely between it and the block *d*⁵, and thereafter the wire will be carried forward with the arm *d*²; but as soon as the arm *d*² is moved in the opposite direction the annulus resting against and biting the wire will instantly draw the annulus forward, or away from the lower end of the holder *d*⁵, and the disk and block *d*⁵ will travel easily backward over and without moving the wire; but at this time the wire will be held by a like annulus mounted on a like hub attached to a fixed arm, 5, of the head or face plate, (see Fig. 3,) the said annulus (herein marked 46, to distinguish it from the one *d*³) operating in connection with a block, 6, and a holder, *e*³, the same in construction as parts marked *d*⁴ and *d*⁵, before described, they constituting a detent for the wire, and preventing the same from being moved backward from any cause as the arm *d*² of the feeding device is moved backward.

I do not limit my invention to the particular devices for grasping the wire as described, and instead thereof may use any other well-known equivalents: The arm *d*² is attached to a rock-shaft, *d*, mounted in a bracket, *d*', attached to the head of the machine. The rock-shaft *d* has attached to it a second arm, *c*', which by the spiral spring *d*¹ is kept pressed against the feed-actuating slide *c*², provided with a roll, *c*², (shown in Fig. 1 and in dotted lines, Fig. 3,) which latter is, by the said arm and spring, kept pressed against the cam-hub *c* referred to, the latter, as the shaft *a* is rotated, vibrating the arm *d*² a greater or less distance, and consequently feeding the wire more or less at each forward stroke. The extent of movement of the arm *d*² is regulated by the feed-regulating screw or device *d*³, held and made adjustable in an ear of the arm *d*², (see Fig. 3,) the said screw co-operating with the projection *d*⁴, fixed to the bracket *d*'.

Assuming the parts to be in the position shown in Fig. 5, which shows the wire 34 about to be passed across one of the plates *n*² at the face of the presser-bar *f*, and the driver *i*' about to force a previously-made staple (shown in full lines in the lower end of the presser-bar) down into the stock supposed to be resting on the anvil 12, the operation of parts, upon giving motion to the shaft *a* by clutching it to the pulley *a*' through the aid of the foot-lever, (not shown,) will be as follows: The feed-lever *d*², through the operation of the connected parts, will be moved toward the cutter-bar 9, in the direction of the arrow thereon, Fig. 3, and, gripping the wire, will draw it from the spool 3 through the grooved rod *r*, and between the annulus 46 and block 6 of the detent, as described, and will force or push a portion of the wire held by and in front of the lever *d*² through the block 9 and across the face of the presser-bar

f and the driver *i'* and into the groove *m²* of the former or lever *m*, when the disposition of parts will be substantially as shown in Fig. 1. While the wire is being fed across the face of the presser-bar and into the groove *m²* in the lower end of the former *m*, the driver *i'* is forcing the previously-made staple through any suitable shoe or other article held on the anvil; which done, the presser-bar will be drawn up into the guides until the transverse groove 20 is brought immediately back of and in line with the portion of the wire held by the former *m* across the face of the presser-bar, at which point the driver-bar *i*, carrying the driver *i'*, having been partly drawn up in its guides, is carried to its highest point in said guides, and its beveled upper end, 25, strikes against the toe 23 of the former *m*, (see Fig. 1,) thus turning the former *m* to force its lower end, yet holding the wire, toward the presser-bar *f*, and as the driver at such position of the driver-bar or carrier is sufficiently elevated to rise above the groove 20 referred to the wire acted upon by the former *m* is pushed into the said groove 20 of the presser-bar, (see Figs. 6 and 7,) and is held therein by the former. This done, the presser-bar will begin its downward movement, whereupon the disk-cutter 33, operating in connection with the end of the block 9, will cut or sever the wire of a proper length for a staple, and the curved or inclined portion 52 of the descending presser-bar *f*, acting as wipers on the ends of the said section of wire fixedly held by the notch *m²* of the former *m*, will effect the withdrawal of the short piece of wire from the groove 20 at each side of the former, producing a staple, as shown in Fig. 8, which will be held in the groove in the path of the driver, so that the driver in its descent will strike the staple. The spring 10 in the groove in the face of the presser-bar acts against the staple after the lower end of the former *m* is thrown out and prevents the staple from tipping over.

I claim—

1. The movable feed-actuating slide and the rock-shaft and its attached arms, combined with means attached thereto to grasp and feed the wire, substantially as described.

2. The movable feed-actuating slide, the rock-shaft and its attached arms, and means attached thereto to grasp and feed the wire, combined with the detent to prevent the backward movement of the wire, substantially as described.

3. The combination, with the grooved block, of the reciprocating bar *f*, having a recess in its side contiguous to the said block, and with a notched or slotted disk held in said recess and co-operating with the block 9 to cut the wire, substantially as set forth.

4. The pivoted lever or former grooved or notched transversely at its lower end, in combination with the transversely and longitudinally grooved presser-bar, and means to reciprocate the same, as described, combined

with means, substantially as described, for throwing the lower end of the former toward and from the presser-bar, for the purpose set forth.

5. The driver bar or carrier, its attached depending driver, and suitable means for imparting a reciprocating movement thereto in the guides *g*, and the said guides *g*, combined with the presser-bar arranged in the said guides below and in the same vertical plane with the driver-bar, and provided with a groove or way in its face for the driver, the said driver-bar and presser-bar being arranged in the guides one above the other, and being independent of each other, substantially as shown and described.

6. The guides *g* for the driver bar or carrier and the driver, and the presser grooved longitudinally for the reception of the driver, and the attached plates *n' n²*, attached thereto, to form or leave a groove or space, 20, for the reception of the wire, combined with the pivoted lever or former, having at its upper ends a toe which rests in the path of the driver-carrier, and its lower end with a transverse groove or notch, to operate substantially as and for the purpose set forth.

7. The longitudinally-grooved presser-bar *f*, the plates *n' n²*, attached thereto, to leave a wire-receiving space, 20, combined with the spring 10, placed in a recess in the presser-bar, to operate substantially as and for the purpose set forth.

8. The combination, with the driver-shaft *a* and cam-wheel fixed thereto, of the longitudinally-grooved presser-bar having the connecting-stud *f'*, and the driver-bar arranged above and in the same vertical plane as the presser-bar, and provided with the depending driver fitting the longitudinal groove of the presser-bar, and the connecting-link, substantially as set forth.

9. The former pivoted at about midway of its length and provided with a cam projection at its upper end, and transversely grooved at its lower end for the reception of the wire before it is severed into staple-forming lengths, the presser-bar transversely grooved for the reception of the wire after it is cut into staple-forming lengths, and a driver-bar having its upper end beveled or reduced and adapted to operate the former, and provided with a staple-driver, as specified, combined with means, substantially as described, to reciprocate the driver and presser bars, and to cut the wire, as set forth.

10. The block *g*, combined with the movable presser *f*, recessed at one side and provided with the notched cutter 33, placed in the said recess, to operate substantially as described.

In testimony whereof I have signed my name to this specification in the presence of two subscribing witnesses.
